TO AMERICAN GAS MACHINE COMPANY, OF ALBERT LEA, MINNESOTA, A CORPORATION OF MINNESOTA.

GAS BURNER FOR STOVES.

Application filed August 3, 1925. Serial No. 47,797.

This invention relates to a gas burner structure such as used with gas or other stoves burning a mixture of gas or hydro-carbon fuel and air. It has heretofore been proposed to construct such a burner comprising a hollow body having substantially vertical sides, apertures for the passage of the gas or combustible mixture being formed in the top and sides of said body, which apertures have sometimes been in the form of slots extending across the top of the body and some distance down along the sides thereof. It has also been the practice to construct burners having a plurality of sections each comprising a body, as above described, which sections have been arranged in parallel relation. It has been found in practice that when the flame on the burner is adjusted to be low or small that the flame does not extend to the openings at the sides of the burner body. There is always a tendency for the gas or combustible mixture to rise from the burner and this tendency is augmented by the draft through and around the burner caused by the heated air above the burner. This upward movement and draft at the burner has caused the flame to be limited to the top surface of the burner, so that there are openings in the burner at which there is no flame and at which the gas or combustible mixture may escape unburned.

It is an object of this invention, therefore, to construct a gas burner having openings therein for the passage of the gas or combustible mixture so arranged that when the flame is turned low the flame will extend to all of said openings and throughout their entire extent.

It is a further object of the invention to provide a burner having a surface through which the openings are formed for the passage of the gas or combustible mixture, all of which surface faces upwardly.

It is still another object of the invention to provide a gas burner having a surface at its top substantially horizontal and having surfaces of its sides inclined downwardly, the passages for the gas or combustible mixture extending through all of said surfaces.

It is still another object of the invention to provide a gas burner having one or more sections with slots extending transversely

thereof for the passage of gas or combustible mixture, said sections being beveled or inclined downwardly at their sides substantially to the bottom of said slots.

It is also an object of the invention to provide a burner comprising a plurality of spaced sections having slots or openings at their tops and sides for the passage of gas or combustible mixture with means for directing the air passing upwardly between said sections away from said section.

These and other objects and advantages of the invention will be fully set forth in the following description made in connection with the accompanying drawings in which like reference characters refer to the same parts throughout the different views, and in which:

Fig. 1 is a top plan view of the burner;

Fig. 2 is a vertical section taken on the line 2—2 of Fig. 1, as indicated by the arrows; and

Fig. 3 is a vertical section taken on the line 3—3 of Fig. 2, as indicated by the arrows.

Referring to the drawings, a burner is shown having a lower hollow cylindrical portion 4 by which it is adapted to be connected to the fuel supply, said section 4 opening into a hollow transverse portion 5, which portion 5, in turn, opens into and is connected to a plurality of transverse sections 6 extending across said body portion 5 and substantially at right angles thereto at each side thereof. The portion 5 thus forms, in effect, a common portion for the transverse sections 6. It will be noted that the sections 6 are separated by the spaces 7 formed therebetween at each side of the portion 5. The burner is provided at its top with a multiplicity of openings 8 for the passage of gas or combustible mixture thereof. While these openings may take various shapes, in the embodiment of the invention illustrated, they are shown as narrow slits or slots extending transversely of section 6 in substantial parallel relation. It will be noted that the top portion of the burner having the slots 8, therefore, extends above the top surface of the portion 5 between the sections and that said projecting portion has the horizontal top surfaces 6^a and the downwardly inclined or beveled surfaces 6^b at

each side thereof, the slots 8 extending down substantially to the bottom of the inclined surfaces 6^b. The sections 6 also have inwardly and downwardly inclined surfaces 6^c below the surfaces 6^b so that the spaces 7 converge at their upper ends.

In operation, the gas or combustible mixture will pass upward through the burner and will issue through the openings 8 where 10 it will be ignited. The flame will extend along the surface 6^a and 6^b and it will be readily seen that the air ascending through the spaces 7 will not come in direct contact with the flame of gas issuing through 15 the openings 8 since the surfaces 6^a and 6^b both face upwardly. The gas issuing through the slots 8 in the surface 6^b is therefore not carried upwardly by the rising air and the same remains ignited throughout 20 the entire length of the openings 8 no matter how small the flame is adjusted. Furthermore, the air rising through the spaces 7 is directed away from the surface 6^b by the inclined surface 6^c so that the 25 tendency of this air to carry the gas or combustible mixture upward in unburned condition is still further lessened. When the burner is operating, therefore, the flame, as stated, extends throughout the entire length 30 of the openings 8 and across the entire portion of surfaces 6^a and 6^b so that there is no opening without flame and through which the gas or combustible mixture may escape unburned. The burner therefore is very efficient 35 for the combustion of the gas or combustible mixture and no unburned gas or combustible mixture can escape to cause an odor.

From the above description it is seen that 40 applicants have provided a very simple and efficient form of gas burner and one which overcomes a serious objection to burners heretofore used. The burner is very simple in construction and easily and inexpensively 45 made. The same has been amply demonstrated in actual practice and found to be very successful and efficient and is now being commercially manufactured.

It will, of course, be understood, that various 50 changes may be made in the form, details, arrangement and proportions of the parts without departing from the scope of applicants' invention, which, generally stated, consists in a device capable of carrying out the objects above set forth, in the 55 novel parts and combinations of parts dis-

closed and defined in the appended claims.

What is claimed is:

1. A gas burner comprising a plurality of spaced elongated adjacent hollow sections, 60 said sections each having a series of spaced slots extending thereacross, the tops of said sections comprising horizontal flat top portions and side portions inclined downwardly therefrom, the lower edge of said inclined portions terminating substantially at the bottom of said slots, said sections having means below said inclined portions for directing the air away from said inclined portions and slots. 65

2. A gas burner comprising a longitudinally extending hollow section having a top surface and having portions with surfaces sloping downwardly at each side thereof, a plurality of slots extending transversely of 70 the top of said section to the edges thereof and communicating with its interior, said section having means at each side below said downwardly sloping portions for directing air away from said portions and slots. 75

3. A gas burner comprising a longitudinally extending section having a flat horizontal top surface and surfaces at each side thereof extending downwardly and outwardly from said surface, a plurality of 80 transverse slots extending across said burner having their bottoms at the lower edges of said downwardly inclined surfaces, said section having downwardly and inwardly inclined surfaces extending from the lower 85 edges of the downwardly inclined surfaces, said section being hollow whereby gas may 90 pass therethrough and out of said slots. 90

4. A gas burner comprising a longitudinally extending section having a flat horizontal top surface and surfaces at each side thereof extending downwardly and outwardly from said surface, a plurality of transverse slots extending across said burner having their bottoms at the lower edges of said 95 downwardly inclined surfaces, said section having downwardly and inwardly inclined surfaces extending from the lower edges of the downwardly inclined surfaces, said section being hollow whereby gas may pass 100 therethrough and out of said slots, said burner having a common chamber with which all of said sections communicate. 105

In testimony whereof we affix our signatures.

WALTER OLSEN.
SOPHUS RASMUSSEN.
